United States Patent Office

Des. 229,992

Patented Jan. 22, 1974

229,992

DISPLAY CABINET OR SIMILAR ARTICLE

Mel Kaiser, Teaneck, N.J., assignor to Automated Learning, Inc., Fairfield, N.J.

Filed June 1, 1972, Ser. No. 258,931

Term of patent 14 years

Int. Cl. D6—04

U.S. Cl. D6—27

FIG. 1

FIG. 3

FIG. 2

FIG. 4

FIG. 1 is a perspective view of a display cabinet or similar article, showing my new design;

FIG. 2 is a side view;

FIG. 3 is a plan view; and

FIG. 4 is a bottom view.

The sides of the cabinet not shown are like the sides shown.

I claim:

The ornamental design for a display cabinet or similar article, substantially as shown and described.
